UNITED STATES PATENT OFFICE.

HARRIET G. NORTHFIELD, OF MINNEAPOLIS, MINNESOTA.

BREECH-CLOTH SUPPORTER.

SPECIFICATION forming part of Letters Patent No. 727,188, dated May 5, 1903.

Application filed January 6, 1902. Serial No. 88,566. (No model.)

To all whom it may concern:

Be it known that I, HARRIET G. NORTHFIELD, a citizen of the United States, residing in the city of Minneapolis, in the county of 5 Hennepin and State of Minnesota, have invented certain new and useful Improvements in Breech-Cloth Supporters, of which the following is a specification.

The present invention relates to means for 10 supporting breech-cloths; and the object is to provide an article of this character that will constitute an efficient supporter and will impart an even tension without regard to the position assumed by the body of the wearer. 15 Another object is to construct the article of a few simple parts so arranged that the joints are reduced to a minimum number and are very strong.

The preferred embodiment of the invention 20 is illustrated in the accompanying drawings, wherein—

Figure 1 is a view showing the supporter when in place upon an infant. Fig. 2 is a 25 plan view, on an enlarged scale, of the supporter. Fig. 3 is a detail sectional view taken on the line *x x* of Fig. 2. Fig. 4 is a detail sectional view taken on the line *y y* of Fig. 2, and Fig. 5 is a detail sectional view taken on the line *z z* of Fig. 2.

Similar numerals of reference designate corresponding parts in all the figures of the drawings.

In the embodiment illustrated a pair of suspender members 10 is employed, comprising 35 spaced substantially inelastic shoulder-straps 11, that are slightly bowed, as shown in Fig. 2. Convergently-disposed elastic terminal bands 12 are secured to the ends of the shoulder-straps, the bands at each end being 40 preferably in the form of a single loop, the ends of which are fastened to the ends of the shoulder-straps. Braces 13, also preferably formed of inelastic material, extend across the space between the two suspender members 45 and are attached to the same at the joints of the shoulder-straps and elastic bands, thus bringing the points of attachment of the braces, straps, and bands together, reducing the number of joints to a 50 minimum, and greatly strengthening them. Any well-known form of fabric joint may be

employed, though for efficiency and cheapness that shown in Figs. 3 and 4 is considered preferable, the parts being sewed together. At the ends of the members, or, in other 55 words, at the points of convergence of the terminal bands 12, are located fastening devices in the form of safety-pins 14, each having an offset looped portion 15, across which extends a bar 16, that is surrounded by the 60 looped elastic band, all of which will be clearly understood by reference to Figs. 2 and 5.

The manner of using the device will be apparent by reference to Fig. 1, and it will be 65 seen that no matter what position the body of the wearer may assume an even tension will be afforded. The article can be manufactured at extremely small cost, and as the joints are reduced to a minimum the liability 70 of disagreeable friction or chafing is correspondingly reduced. At the same time the joints are very strong, so that the parts are not liable to pull apart. In this structure there is no need for adjustment, as the 75 terminal pins can be adjustably attached to the cloth, and the one in front is employed for securing the ends of the same together.

From the foregoing it is thought that the 80 construction, operation, and many advantages of the herein-described invention will be apparent to those skilled in the art without further description, and it will be understood that various changes in the size, shape, proportion, and minor details of construction 85 may be resorted to without departing from the spirit or sacrificing any of the advantages of the invention.

Having thus described my invention, what 90 I claim as new, and desire to secure by Letters Patent, is—

1. In a supporter of the character described, a pair of suspender members comprising spaced substantially inelastic shoulder-straps, and convergently-disposed elastic terminal 95 bands secured to the ends of the shoulder-straps, in combination with fastening devices secured to the convergent ends of the terminal bands, and braces extending across the space between the members and secured thereto at the joints of the straps and bands, thereby strengthening said joints. 100

2. In a supporter of the character described, the combination with fastening - pins having cross-bars, of a pair of suspender members comprising substantially inelastic spaced
5 shoulder-straps, looped elastic terminal bands having their ends secured to the ends of the shoulder-straps, said bands surrounding the cross-bars of the fastening-pins, and braces

extending across the space between and connecting the suspender members. 10

In testimony whereof I have hereunto set my hand this 14th day of December, 1091.

HARRIET G. NORTHFIELD.

In presence of—

MINNIE E. CASTNER,
FRANK H. CASTNER.
